UNITED STATES PATENT OFFICE

WILLIAM R. STRICKLAND, OF DETROIT, MICHIGAN, ASSIGNOR TO GENERAL MOTORS CORPORATION, OF DETROIT, MICHIGAN, A CORPORATION OF DELAWARE

TEMPERATURE CONTROL FOR OIL

Application filed May 7, 1928. Serial No. 275,739.

It has proven difficult to maintain the oil in modern high speed, high compression internal combustion engines at sufficiently low temperatures to insure retention of its lubricating properties. Under some conditions it has been found that the oil reaches a temperature as high as 250° F. At these temperatures its efficiency as a lubricating agent is low due to its greatly reduced viscosity. 5 More or less permanent deterioration of the oil also results from the excessive heat. It has been found by tests to be very desirable to maintain the oil supply at temperatures not exceeding 170° F. 10 I propose to maintain the oil at the desired lower temperature by providing a cooling system including a heat absorbing element or cooler located in the crankcase or other oil receptacle and circulating through the cooler 15 a suitable fluid in such manner that the fluid absorbs the heat from the oil, is vaporized and subsequently condenses and returns to the cooler. By this arrangement I make use of the latent heat of the fluid as a factor 20 in cooling and am enabled to conduct away a large amount of heat with a cooler of small size and with the employment of a relatively small quantity of cooling liquid. The inventive idea is susceptible of great variation in 25 its practical embodiment. In the simplest form the cooler is arranged in a by-pass in the engine cooling system and receives water therefrom under a slight head or degree of pressure, this pressure however being insufficient to cause active flow of water through the 30 cooler prior to boiling.

As a modification of my system I may provide a separate radiator or condenser for the vapor generated in my cooler instead of employing the engine cooling radiator for the purpose. In such event I may make use of some fluid other than water as the cooling medium. Such fluids as alcohol, having boiling temperatures around 170°, have advantages for this purpose because the latent heat becomes an effective factor in cooling long before the oil has reached undesirably high temperature. Fluids with even lower boiling points would have greater advantages in this 35 respect.

Instead of locating the cooling coil in the crankcase I may arrange to pump the crankcase oil through a lubricant reservoir equipped with a suitable cooler. This variation may be made in either of the forms of the 55 invention previously described.

All of the forms of my invention possess the advantage that the cooling is accomplished by means of a cooling system of maximum effectiveness and of minimum size, this 60 advantage resulting from the employment of the latent heat of the fluid.

In the drawing:

Figure 1 is a diagrammatic view showing the application of one form of my invention 65 to an internal combustion engine.

In Figure 2 I have shown a modified form in which the oil cooler is connected to a separate radiator.

In Figure 3 I have shown a further modification in which the oil from the engine is forced through a cooling chamber separate from the engine crankcase, this chamber containing a cooler in the form of a radiator through which fluid is circulated. The cooling liquid may be condensed in either of the 70 ways shown in Figures 1 and 2.

In Figure 1, 10 indicates an internal combustion engine provided with the usual radiator 12 for the engine cooling system. This 80 radiator may be of the conventional type provided with top and bottom tanks connected by a honey comb or finned tube core. It is illustrated as of the vertical flow type but a cross flow radiator may be used if preferred. 85 The pump 14 draws water from the bottom tank of the radiator and supplies it to the water jacket of the engine through any suitable conduit shown at 16. The water which has performed its function of cooling the engine is conducted to the top tank of the radiator through conduit 18. The specific cooling system illustrated is conventional and may be varied as desired. 20 indicates the crankcase of the engine within which is located an oil 90 cooler 22 in the form of spaced headers 24 and 26 connected by parallel tubes 28. This cooler is likewise conventional and may be modified as desired. A pipe 30 leads from a suitable point in the cooling system, such 95 100

as the lower tank, to the bottom of the header 24 and a tube 32 leads from the top of this same header to a higher point in the cooling system. I have preferred to project the upper 5 end of the tube 32 into the connection 18 with its open end 34 facing in the direction of water flow so that it is subject to the suction produced by the circulating cooling water.

With this arrangement it is apparent that 10 the water in the cooler 22 is practically static. It will remain so until it absorbs sufficient heat from the oil to cause it to boil. Steam will then be discharged through the outlet 34 and will be condensed either by contact 15 with the following stream or in the radiator 12.

Obviously the connection of the oil cooler with the engine cooling system may be made at other points than those shown. The pipe 20 32 may lead to the upper tank of the radiator 12 if preferred.

By this arrangement it is apparent that the latent heat of the fluid in the cooler 22 is utilized to cool the oil so that a less quantity 25 of cooling fluid is required than would be the case were this phenomenon not relied upon.

In the modification shown in Figure 2 the pipes 30' and 32' connecting with the oil cooler 30 are connected to a separate condenser 40. This may be located in any convenient place.

In the modification shown in Figure 3 the oil cooler 48 is shown located in an oil reservoir 42 supplied with oil from the crankcase 35 20 by means of pump 44 and conduits 45 and 46. The cooling fluid supplied to the oil cooler 48 may either be provided with its own condenser, as shown in Fig. 2, or the radiator of the engine cooling system may be employed 40 for this purpose as shown in Figure 1.

Since the rate of heat exchange between the oil and the cooling fluid depends on the difference in temperature between them it may be found desirable in some instances to use some 45 fluid other than water as the cooling medium. Such fluids should have boiling points lower than water in order that boiling may take place while the temperature difference between the oil and the cooling fluid is greater 50 than in the case of water, thus for some purposes alcohol may prove satisfactory.

I claim:

1. The combination of an internal combustion engine provided with a lubricating system 55 including a lubricant reservoir, a cooler in the reservoir containing a cooling fluid, a condenser, connections between the cooler and the condenser, the cooler being so arranged as to maintain the fluid in static state until circulation is produced by boiling of the fluid, thereby making use of the latent heat of the fluid as the means of heat transfer.

2. An oil cooling system for an internal combustion engine provided with cooling 60 means and with a lubricant reservoir, com-

prising a fluid containing oil cooler associated with the reservoir, a condenser, connections from the cooler to the condenser, said system being independent of the engine cooling means, and said cooler being arranged so 70 that the cooling fluid is non-circulating until boiling takes place.

In testimony whereof I affix my signature.

WILLIAM R. STRICKLAND.
